UNITED STATES PATENT OFFICE

1,926,978

EVAPORATING COIL STRUCTURE FOR
REFRIGERATING SYSTEMS

Norman H. Gay, Los Angeles, Calif.

Application December 28, 1931
Serial No. 583,518

9 Claims. (Cl. 62—126)

This invention concerns a construction of evaporating coils for refrigerating systems in which a free flow of refrigerant is provided between inlet and outlet headers and back again, 5 and concerns certain modifications of the structures shown in my Patents Nos. 1,715,828 of June 4, 1929 and 1,794,110 of February 24, 1931.

In these prior patents I have disclosed a refrigerating or evaporating coil for refrigerator systems in which an inlet and an outlet header are provided with U-shaped coils connecting the same, together with means for returning liquid refrigerant from the outlet header to the inlet header. In Patent No. 1,715,828, this return is 10 illustrated as comprised of an accumulator section which is vertically disposed external to the brine tank or from the enclosure surrounding the true evaporating coils. In my Patent No. 1,794,110, the accumulator is illustrated as a connection between the inlet and outlet headers and has an upper member on the outlet header for the purpose of separating the refrigerant gas.

According to the present invention, the upper or outlet header is made of larger diameter than 25 the inlet header, and this in itself provides a space within which the liquid refrigerant entering the same may remain substantially quiescent for a period, during which the gaseous refrigerant is separated therefrom and passes to the upper space 30 of this outlet header, from which it may be drawn off in the usual way.

Another feature of the present invention is the provision of evaporation coils connecting the headers which are of greater section at the connection to the outlet header than at the connection to the inlet header.

These and other features of the invention will appear in the course of the following specification and claims in connection with the drawing which 40 illustrates one form of construction of an evaporator according to the present invention.

In the drawing:

Figure 1 is an end elevation of an evaporator, 45 with a diagrammatic showing of its connection in cycle with the compressor, condenser and receiver.

Figure 2 is a sectional view substantially on line 2—2 of Figure 1.

As in my prior patents, the compressor 10 is connected by a pipe line 11 with a condenser 12 which delivers condensed liquid refrigerant by 50 a pipe 13 into a combined receiver and oil trap 14 from which the liquid refrigerant flows through a pipe 15 past an expansion valve 16. Trapped oil may flow off through a pipe 17 controlled by a valve 18.

The evaporating coil according to the present 55 invention is illustrated as enclosed within the walls 20 and floor 21 of the brine tank.

The pipe 15 leads into a lower or inlet header 25 from which, in the illustrated form, are branched the pluralities of evaporating coils 26, which are shown in Figure 1 as each being located substantially in a vertical plane extending at right angles to the axis of the inlet header 25; the area of cross section at the connection to the inlet header being less than the cross section at the connection to the outlet header. In Figure 2, each of the coil sets 26 is illustrated 70 as comprising two pipes 27, 28 which communicate with the inlet header 25, and which are connected to the upper or outlet header 29. The pipes 27 are branched intermediate their length to form the branch pipes 27a, 27b and 28a, 28b. 75 In the form of construction shown, this is accomplished by having the pipes 27, 27a, 27b and 28, 28a, 28b of the same diameter throughout. The pipes 27, 28 are substantially horizontal, 80 with a slight upward inclination in their runs away from the inlet header 25, and may be formed integral with the pipes 27a, 28a by bending, the upper runs of pipes 27a and 28a likewise having a slight upward inclination to the connection with the outlet header 29, to facilitate the free movement of the refrigerant from 85 the inlet to the outlet header 29. The pipes 27b, 28b are branched from pipes 27, 28 at the lower substantially horizontal portion of these 90 pipes.

The two headers are connected likewise by large interconnections 30, 31 so that liquid refrigerant passing into the upper header may flow directly back into the lower header, by 95 gravity.

In operation, as the liquid refrigerant from the receiver 14 passes by pipe 15 and valve 16 into the lower header, it establishes a liquid level to substantially half the height of the upper or outlet header 29. Due to the large area 100 of exposure of the coils 26 to the brine in the brine tank, these coils 26 absorb heat from the brine and transfer it to the liquid refrigerant existing in the coils, thus evaporating a portion 105 of the liquid refrigerant. The mixed gaseous and liquid refrigerant then moves upward in the coils, and establishes a rapid circulation from the inlet header through the pipes of the respective coils to the outlet header, and the liquid refrigerant thence goes back by interconnections 30, 31 to the inlet header for return in cycle. Owing to the large diameter of the outlet header, the liquid remains in substantial quiescence 110 in the upper header for a time sufficient to permit the separation and escape of gaseous refrigerant therefrom, before the liquid refrigerant has passed into the inlet header and then to the coils again, and preferably before the 115 120 coils again.

liquid refrigerant passes downward in the inter-
connections 30, 31.

It has been found by experience that the heat
transfer in refrigerating coils increases as the
speed of the liquid refrigerant passing through the
coils increases. By providing a greater cross sec-
tion, for example, by the pipes 27a, 27b, and 28a
and 28b, at the connection to the outlet header
29 than is the cross section of pipes 27 and 28
10 at the connection to the inlet header 25, the
increase in volume caused by the evaporation
of liquid refrigerant occurring in the coils them-
selves, whereby the volume of combined gaseous
15 and liquid refrigerant is greater than the vol-
ume of liquid refrigerant entering the pipes 27
and 28 from the inlet header 25, there is a com-
pensation by the increased cross sectional area
20 of pipes 27a, 27b, and 28a, 28b, and hence a
more rapid flow of refrigerant occurs in the lower
runs, i. e. in pipes 27 and 28 to the branches.
Therefore, on the one hand the flow through
the lower runs is not retarded by the back pres-
sure of the increasing volume of refrigerant due
25 to evaporation, and on the other hand the am-
ple cross section afforded this increased volume
permits it to flow at a greater rate.

In particular, it will be noted that in the illus-
trated form no attempt need be made to sepa-
30 rate gaseous and liquid refrigerant in the evap-
orating coils themselves; and hence full advan-
tage can be taken of the lesser density of the
mixed gaseous and liquid refrigerant for caus-
35 ing a rapid circulation through the coils, head-
ers and return connection, and this rapid cir-
culation in itself serves to restrict any separa-
tion from occurring in the coils themselves.

The inlet header 25 may be provided with a
baffle 40 if desired, so that a substantially quies-
40 cent beneath the same may exist, and an oil
withdrawal pipe 41 may be provided to remove
trapped oil from the inlet header.

It is obvious that the invention is not limited
solely to the form of execution shown but that
45 it may be modified and employed in many ways
within the scope of the appended claims.

Having thus described my invention, what I
claim as new and desire to secure by Letters Pat-
ent, is:—

50 1. An evaporator structure for refrigerating
systems comprising a lower inlet header, an up-
per outlet header of larger cross section than said
inlet header, evaporating coils connecting the
said headers to provide a flow of refrigerant be-
55 tween said inlet header and said outlet header,
each said coil comprising a branched conduit hav-
ing a single connection to said inlet header and
a plurality of connections to the outlet header,
and a liquid refrigerant return connection from
60 said outlet to said inlet header, said outlet header
being of large cross section with respect to said
coils whereby to assure a period of substantial
quiescence in the circulation of the liquid refrig-
erant so that gaseous refrigerant may separate
65 therefrom in said outlet header.

2. An evaporator structure for a refrigerating
system comprising inlet and outlet headers, evap-
orating coils for establishing communication be-
70 tween said headers, at least one of said coils com-
prising a branched conduit having a single connec-
tion to said inlet header and a plurality of
connections to the outlet header, and a liquid
refrigerant return connection between said head-
ers.

3. An evaporator structure for a refrigerating
system comprising inlet and outlet headers, and
an evaporator coil for establishing communica-
tion between the headers, said coil comprising a
80 pipe communicating with said inlet header and
branching along its length into a plurality of
pipes which communicate with said outlet header.

4. An evaporator structure as in claim 3, in
which said coil has a substantially horizontal
runway from the inlet header and at least one
85 branch occurs along such run.

5. An evaporator structure for a refrigerating
system comprising inlet and outlet headers, an
evaporator coil for establishing communication
between the headers, said coil comprising a pipe
90 communicating with said inlet header and
branching along its length into a plurality of
pipes which communicate with said outlet header,
and a liquid refrigerant return connection be-
tween said outlet and inlet headers. 95

6. An evaporator structure for a refrigerating
system including a lower inlet header, an upper
outlet header of larger cross section, and a plu-
rality of evaporating coils for establishing com-
munication between said headers, at least one of
100 said coils being branched between the inlet head-
er and the outlet header and having a greater
section at its connections to the outlet header
than at its connection to the inlet header, and a
liquid refrigerant gravity return connection from
105 said outlet to said inlet header, said outlet header
having a large cross section with respect to said
coils whereby to permit a substantial quiescence
of the refrigerant in said outlet header so that
gaseous refrigerant may become separated from
110 liquid refrigerant therein.

7. An evaporator structure for a refrigerating
system comprising inlet and outlet headers, said
outlet header being located at a higher level than
said inlet header and parallel thereto, a plurality
115 of evaporating coil systems located in planes at
right angles to the axes of said inlet and outlet
headers, each said system including at least one
evaporating coil including a branched conduit
having a greater number of connections to the
120 outlet header than to the inlet header, and a
liquid refrigerant return connection between said
headers.

8. An evaporator structure for a refrigerating
system comprising a low inlet header, an upper
outlet header, a plurality of evaporating coils
125 for establishing communication between said
headers, each of said coils including a substan-
tially U-shaped portion with upper and lower
130 legs which are substantially horizontal and a
further and branched portion extending from the
lower leg to the outlet header, and a liquid refrig-
erant gravity return connection from said outlet
to said inlet header. 134

9. An evaporator structure for a refrigerating
system comprising inlet and outlet headers, said
outlet header being located at a higher level than
said inlet header and parallel thereto, a plurality
140 of evaporating coil systems each located in a
plane at right angles to the axis of said inlet and
outlet headers, each said system including a plu-
rality of branched conduits each having a U-
shaped portion with the legs horizontal and a
145 branched connection from the lower horizontal
leg to the outlet header, and a liquid refrigerant
return connection between said headers.
